BAR TURNING DEVICE

Edward T. Peterson, Reading, Pa., assignor to
 Birdsboro Steel Foundry and Machine Company, Birdsboro, Pa., a corporation of Pennsylvania

Application July 13, 1949, Serial No. 104,425

4 Claims. (Cl. 80—53)

1

The present invention relates to turning devices for rolling mill use, especially to roller devices capable of operating on moving bars.

A purpose of the invention is to turn a bar travelling along a mill table through a suitable angle on an axis within the stock for the purpose of correctly entering the bar into a wire guide or into a grooved roll.

A further purpose is to turn a bar as it travels continuously through the rollers of a turning device.

A further purpose is to mount gripping rollers on a hollow trunnion, to support the trunnion on a trunnion bearing or bearings and to rotate the gripping rollers and the trunnion by a thruster desirably set in operation at the exact time of the entry of the stock into the gripping rollers.

Further purposes appear in the specifications and in the claims.

The drawings illustrate one only of the numerous embodiments in which the invention may appear, the form shown being selected from the standpoints of convenience in illustration, satisfactory operation and clear demonstration of the principles involved.

Figure 1 is a side elevation of the turning device of the present invention.

Figure 2 is a rear end elevation of Figure 1.

Figure 3 is a top plan view of Figure 1.

Figure 4 is a section through the trunnion on the line 4—4 of Figure 3.

Figure 5 is a circuit diagram and hydraulic diagram illustrating the operation.

In the drawings like numbers refer to like parts throughout.

Describing in illustration but not in limitation and referring to the drawings:

In the rolling of metallic stock, such as billets, blooms, bars, or the like, herein generally designated as "bars," it is common practice after an individual rolling mill roll pass, to turn the material being rolled on its longitudinal axis, usually by hand, and ordinarily through an angle of 90°. Thus the direction of the cross section which was horizontal in the previous pass becomes vertical in the next pass.

In the prior art the turning of the material being rolled has in many cases been accomplished by hand. In other instances a moving side guard and finger lift has been employed to accomplish the turning movement. Various other manipulators have been devised, which require gripping of the material being rolled

2

while it is substantially stationary and turning the material being rolled.

The various prior art turning procedures are generally subject to the disadvantage that it is necessary to operate on the material being rolled when it is stationary or moving very slowly, and thus in general it is usually not possible to turn the material being rolled reliably and effectively between passes on high speed continuous mills. 10 An effort to overcome this difficulty has been made by passing the billet through a passage having stationary channels which impart a twist with limited success, due to great loss of speed, and with considerable danger of abrading and tearing the outer surfaces as the material being rolled encounters the screw channels.

In accordance with the present invention a turning device has been developed which is capable of operating on moving stock between 20 passes on a continuous rolling mill or under other conditions in which a high speed of forward progression is being maintained. By proper adjustment the turning can be accomplished even where the bar is of comparatively short length moving at high speed, and therefore remains in the rollers only for a very short time. No appreciable marring of the outer surface of the bar occurs, and the device is not limited by the speed of forward progression.

The bar passes longitudinally through a space 20 between a plurality, preferably a pair of gripping rollers 21 and 22. The rollers are desirably grooved at 23 and the grooving may have any suitable contour. The rollers are mounted on shafts 24 which are pivoted to idle freely on anti-friction bearings 25 supported in a trunnion 26. The bearings are held by caps 27 held in place by screws 28 and the ends of the anti-friction bearings are enclosed by covers 30.

The trunnion has a passage 31 extending longitudinally from end to end and has a center recess 32 in which the rollers operate. Forwardly and rearwardly of the rollers on the trunnion are trunnion bearing surfaces 33 suitably on the same axis as the longitudinal axis of the bar going through between the rollers and rockably supported in trunnion bearings 34 on a frame 35. The trunnion bearings have caps 36 held in place by studs 37.

The passage 31 through the trunnion is approached at the forward end by a belled inlet portion 38, generally conical in form, and at the rearward end has a further belled outlet portion 40 and a straight portion 41 at the extreme rear.

A collar 42 forms the forward portion of the trunnion and a collar 42' forms the extreme rearward portion. A funnel shaped guide 43 is stationarily mounted on the frame behind the trunnion.

Secured desirably integrally to the trunnion at its rear end is a crank 44 extending radially outwardly and pivotally connecting at 45 at its outer end with links 46. The opposite ends of the links 46 pivotally connect at 47 with a crank 48 fixed on a crank shaft 50 having bearing support at 51 in the frame. The crank shaft 50 carries secured thereto spaced cranks 52 which pivotally connect at 53 to pull rods 54. The shaft is counterweighted at 50'. The pull rods pivotally connect at their upper ends with a cross brace 55 which is mounted on dual piston rods 56 of a thruster 57. The thruster 57 may be of any of the well known types, conveniently consisting of a cylinder 58 (Figure 5) having a piston 60 which is urged by a spring 61 toward its downward position and raised by hydraulic fluid, suitably oil, passing through a pipe 62 from a reservoir 63 under the action of a pump 64. The pump may desirably be a centrifugal pump, in which case 25 the return of the hydraulic fluid when the pump ceases to operate can occur through the pipe 62, going back to the reservoir. The reservoir is desirably connected to atmosphere through a check valve 65.

The pump is suitably driven by an electric motor 66 connected to a source of electric current 67 by a switch 68. The switch is of the well known flag switch type having an operating flag 70 which is positioned in the path of the bar a short distance, suitably a few feet, ahead of the turning device, so that the thruster will begin to operate to overcome the inertia of the moving parts before the bar actually reaches the gripping rollers, and thus it will be possible to turn the 40 gripping rollers through approximately 90° during the short time that the bar is moving through them. In this way the device is able to operate as a moving turning device or manipulator. The usual position for the mechanism will be on the 45 center line of the entering roll pass and a certain distance ahead of the roll stand to give the turning device time to complete its turning motion before the moving bar enters the wire guide of the roll stand.

In operation, as the bar approaches from the previous pass it encounters the flag 70 and closes the switch 68, starting the motor 66 which operates the pump 64 and begins to introduce hydraulic fluid into the cylinder 58 to raise the 55 piston 60 and to force the dual piston rods 56 upward. This raises the pull rods 54, turning the cranks 52 and turning the shaft 50. The shaft swings the crank 50 and through it the links 46 to swing the trunnion in the trunnion bearings through an angle suitably 90°. The turning of the trunnion turns the rollers mounted thereon, and since the rollers grip the bar as soon as it reaches them, the billet is likewise turned.

The timing is adjusted so that the operation of the thruster prior to the time that the billet reaches the rollers is sufficient merely to overcome inertia without extensive angular motion of the trunnion, so that substantially all of the 70 angle motion occurs while the billet is travelling through the rollers, and is therefore converted into turning movement by the rollers. As soon as the billet leaves the flag the switch 68 opens, but the bar will leave the rollers before there 75

has been time for the thruster to return to starting position.

It will be evident that the device can also be employed on stationary or slowly moving bars by hand closing of the switch 68, in which case it will not be necessary to start the operation of the thruster in advance of the entry of the billet into the rollers. Likewise when the sectional reduction of the stock has extended far enough so that the stock is of great length, even though it may be moving at high speed, it may not in all cases be necessary to start the operation of the thruster in advance of the entry of the bar into the rollers.

It will be evident that the thruster has the advantage over other driving devices that it gives very rapid operation, since a considerable amount of energy is available to turn the trunnion.

In view of my invention and disclosure variations and modifications to meet individual whim or particular need will doubtless become evident to others skilled in the art, to obtain all or part of the benefits of my invention without copying the process and apparatus shown, and I, therefore, claim all such insofar as they fall within the reasonable spirit and scope of my claims.

Having thus described my invention what I claim as new and desire to secure by Letters Patent is:

1. In a bar turning device, a pair of cooperating turner rollers adapted to engage a bar moving forward, a trunnion rotatably supporting the rollers and rockable about an axis longitudinal of a bar passing through the rollers, a trunnion bearing rockably supporting the trunnion, a thruster, an electric drive for the thruster, a switch contacted by the bar in advance of the rollers, an electric circuit including the switch and the drive, and levers for connecting the thruster and trunnion.

2. In a bar turning device, a set of rollers rotatable on axes transverse to the motion of a bar and positioned on opposite sides of the path of the bar in position to grip the bar, a hollow trunnion having two bearings for each roller and having two trunnion surfaces, one forward and one rearward of the rollers, trunnion bearings for each trunnion surface, a thruster, an electric drive for the thruster, a switch contacted by the bar in advance of the rollers, an electric circuit including the switch and the drive, and levers for connecting the thruster and the trunnion.

3. In a bar turning device, a pair of cooperating turner rollers adapted to engage a bar moving forward, a trunnion rotatably supporting the rollers and rockable about an axis longitudinal of a bar passing through the rollers, a trunnion bearing rockably supporting the trunnion, stroke mechanism operatively connected to the trunnion and having an angular throw of approximately 90° on the trunnion within a time less than the time of travel of the bar through the turner rollers, and a tripping device actuated by the bar as it travels toward the turner rollers and operatively connected to the stroke mechanism for energizing the stroke mechanism.

4. In a bar turning device, a set of turner rollers rotatable on axes transverse to the motion of a bar and positioned on opposite sides of the path of the bar in position to grip the bar, a hollow trunnion having two bearings for each roller and having two trunnion surfaces, one forward and one rearward of the rollers, trunnion bearings supporting the trunnion surfaces, a thruster reciprocable over a stroke, levers con-

necting the thruster and the trunnion and angularly throwing the trunnion through a stroke of 90° as the thruster moves through its stroke, and a tripping device placed in the path of the bar before it reaches the turner rollers and operatively connected to the thruster to actuate the thruster.

EDWARD T. PETERSON.
